UNITED STATES PATENT OFFICE.

LOUIS PHILIP PUTT, OF TORONTO, OHIO.

HAIR CURLER.

Application filed July 11, 1922. Serial No. 574,230.

To all whom it may concern:

Be it known that I, LOUIS P. PUTT, a citizen of the United States, and a resident of Toronto, in the county of Jefferson and State 5 of Ohio, have invented certain new and useful Improvements in Hair Curlers, of which the following is a specification.

This invention relates to improvements in hair curlers.

10 The present invention more particularly relates to the type of hair curler in which one or more strands of flexible wire are employed, said wires being of a predetermined length and properly secured together and 15 about which hair may be wrapped and secured. With a curler of this type it often occurs that the hair becomes disengaged from the curler and causes considerable inconvenience.

20 With the above in mind it is the object of the present invention to provide a hair curler of this character whereby the disadvantage heretofore referred to may be avoided.

25 It is also within the scopes and objects of the invention that the curler be extremely simple in construction, easy to manipulate and not injurious to the hair.

Other objects and objects relating to details of construction will hereinafter appear.

The invention is illustrated by way of example in the accompanying drawing, in which

Figure 1 is a perspective view illustrating the application of the invention,

Figure 2 is a perspective view of the curler when complete as an article of manufacture, and

Figure 3 is a detailed perspective view 10 showing the curler in the stage of construction.

Referring to the drawings more particularly the device may consist in two flexible strands W which are of the same length and 15 each strand W may consist in a wire 10 covered with a fabric casing 11. In fact the strands W may each be of a section of insulated copper wire such as used for electrical conductors. The strands W may, of course, be made of other material which would have the same flexibility.

In forming the curler, the strands W are placed together and the end portions thereof wrapped about each other to provide the 20 two twisted portions 12 and intermediate these portions are the portions 13 which are

free from each other. The twisted portions 12 may now be wrapped with thread or the like as indicated at 14 (Figure 2) and the ends of the wires may be covered with 60 sealing wax or the like as at 15. Also the portions 13 of the strands may be slightly twisted about each other as shown in Figure 2. The curler is now ready for the market and a number of these curlers may 65 be placed in one receptacle for shipment or storage.

Where it is desired to use one of the curlers the middle portions 13 of the strands W are disengaged from each other and arranged 70 to provide a loop as illustrated in Figures 1 and 3 of the drawings. A plurality of strands of hair may be extended through this loop as shown in Figure 1 and then the end portions 12 of the strands may be 75 grasped and turned over so that the middle portions 13 are again twisted and thereby to bind the strands of hair therebetween. Preferably the binding at this time is slight so that the curler may be slipped upon the 80 strands of hair to the desired position. Usually the curler is slipped to a point near the ends of the strand of hair and at this time the portions 12 may be further twisted in order to effect an exceedingly tight hold 85 upon the hair. The curler now may be rotated about its longitudinal axis and the strands of hair held therein wound thereabout, that is about the segmental portions 13 and after the hair has been fully wound 90 thereon the end portions 12 of the curler may be bent inwardly and toward each other and upon the hair and thus effecting a means for holding the curler in this position.

What I claim is:

1. A hair curler comprising a pair of elongated flexible elements having similar end portions twisted about each other and their central portions free from each other and curved to form a pair of opposed arcs 100 to provide a loop through which a lock of hair may be extended and whereby with the twisting of the elements, the loop may be closed and a lock of hair clamped between said elements.

2. A hair curler comprising a pair of flexible wires covered with fabric and having similar end portions twisted together and their central portions free from each other, a wrapping about the twisted portions, 110 and a wax covering the ends of said wires.

LOUIS PHILIP PUTT
